C. A. SPOTZ

CLOSURE FOR PASTE TUBES AND THE LIKE

Filed April 18, 1925

Inventor:

Chester A. Spotz,

by *Samuel M. Miller, Donald W. Hall*
Atty's.

UNITED STATES PATENT OFFICE.

CHESTER A. SPOTZ, OF GREENWICH, CONNECTICUT.

CLOSURE FOR PASTE TUBES AND THE LIKE.

Application filed April 18, 1925. Serial No. 24,209.

My present invention relates to improvements in closure means for collapsible tubes of the type used as containers for tooth paste, shaving cream, paints, and other plastic materials, or articles.

The invention aims to provide a construction in which the closure cap may be readily connected to and disconnected from the tube, spout or nozzle, by a swinging motion, 10 as distinguished from the customary screwing and unscrewing, and in which the cap will be permanently connected with the tube so as to insure it against loss or displacement, and by which it may, in effecting closure, be properly aligned with the tube nozzle.

The invention further aims to provide a tube having associated with such closure device, means whereby the container may be 20 suspended from a hook or nail, where this is desirable.

The invention further aims to accomplish the aforesaid objects by means which will be economic of manufacture, and durable and 25 efficient in use.

With these various objects in view, the invention includes the novel features of construction and arrangement and combination of parts hereinafter described, the precise 30 nature and scope of my invention being defined and ascertained by the claims appended hereto.

An embodiment of the invention is illustrated in the accompanying drawing, in 35 which:—

Figure 1 is a perspective view of the upper portion of a paste tube with my improved closure means applied thereto.

Fig. 2 is a side elevation.

Fig. 3 is a central vertical transverse section.

Fig. 4 is an elevation looking from the right, Fig. 2.

Fig. 5 is a top or plan view with the parts 45 shown in the position of Fig. 1.

Fig. 5^a is a sectional detail showing the lug and slot formation of the cap, and

Fig. 6 is a view showing a modified form of suspended means.

Referring by reference characters to this drawing, the numeral 1 indicates the collapsible body of the tube having the customary relatively rigid head 1^a carrying the delivery spout or nozzle 2. This may be 50 shaped to deliver the paste in any desired

form, to wit, either of circular cross section, or of flattened or ribbon form.

In the preferred embodiment I have shown the nozzle as of transversely elongated form with the paste exit opening 2^a of corresponding shape.

The nozzle is provided on opposite sides with grooves 2^b adapted to receive the holding means hereinafter described.

3 designates the cap which has an internal bore or recess to fit the nipple, both of which may be tapered to effect a tight joint. The cap may, also, be provided with an internal elastic packing, such as a layer of cork 3^a to further secure an air tight closure.

The wall of the cap is provided on diametrically opposite sides thereof, with lugs or projections 3^b which have grooves or channels 3^c in their outer faces forming shoulders, and said wall is further provided with a semi-circular slot 3^d extending from lug to lug. The head 1^a of the container is provided with a lug or projection 1^b having a groove or channel, one wall 1^c of which is elongated and of bendable material for a purpose which will presently appear, and which before assembly projects outwardly to leave an open slot in the lug.

4 designates a closure carrying and securing member formed of spring wire having approximately parallel cap carrying side arms 4^a, and an intermediate or connecting transverse portion 4^b which is designed to be inserted in the groove or channel in the lug 1^b, whereafter the bendable wall is overturned or pressed down to close the slot and form a closed eye in which the portion 4^b is rotatably held, thereby forming a pivot or hinge for said side arms. The arms are preferably offset or bent outwardly due to the fact that it is undesirable or unnecessary to make the hinge lug as wide as the cap.

Immediately adjoining these offset lug engaging portions 4^a, Fig. 5, the arms are bent sharply inward towards each other to provide two tongue portions 4^d which enter the semi-circular slot in the cap from opposite sides and project far enough, when unrestrained, to enter the grooves 2^b in the spout or nozzle when the cap is in place thereon. After forming these tongues the wires constituting said arms are carried outwardly (away from the hinge) through the slots and are then bent to extend past each other in opposite directions, as indicated at

4°, their termini being provided with thumb and finger grasping means, such for example as the loops 4°.

From the foregoing, it will be readily seen that when the cap is in place on the tube nozzle, it will be securely locked in position by the projections of the spring arms engaging the grooves in the opposite side of the nozzle, while to remove the cap, it is only necessary to press the two loops 4° towards each other, which withdraws the projections or locking tongues from the nozzle grooves and allows the cap to be swung away from the nozzle on the pivot formed by the engagement of the carrying arms with the lug on the container head.

To replace the cap, it is only necessary to swing it over against and press it upon the nozzle, the taper of which forces the arms apart until they are aligned with the nozzle grooves, when they immediately spring into locking position.

It is desirable to provide means for hanging a paint tube of this character on a hook or nail. To this end I provide the cap with a lug 5 on the top thereof, having a groove therein provided with an elongated bendable wall 5°. By inserting a ring 6 in this groove and bending over the wall 5° to form a closed eye, the ring will be held in place and ready for use as a suspending means.

If desired, the ring attaching lug could be applied to the end wall or head 1° of the tube, as indicated at 5° in Fig. 6.

It is obvious that instead of making the hinge lug 1° with one short and one long bendable wall, it could be made with two bendable walls or tongues of equal length, both adapted to be bent over towards each other to close the slot and form the hinge eye.

It will also be obvious that, if desired, suspending means such as ring 6 could be omitted and one of the loops 4° used for hanging the tube on a hook or the like.

It will be observed from Fig. 6 that the grooved projection 1° has one portion or wall higher than the other portion on the opposite side of the groove. This construc-

tion is important because in the formation of the tube it is desirable to use as little material as possible, it being understood that the tube is formed, together with the projection, by a die operation. In assembling the hinged member with the lug of Fig. 6 the pintle or hinge portion of the cap carrier is seated in the groove and the taller wall 1° is bent over this pintle upon the shorter wall of the lug.

Having thus described my invention, what I claim is:

1. In combination, a container having a delivery nozzle provided with shoulders on opposite sides thereof, a cap for said nozzle, and hinge means connecting the cap to the container, said hinge means comprising spring arms having portions to engage said shoulders, and having crossed ends.

2. A device according to claim 1, in which the shoulders on the nozzle are provided on opposite sides with grooves which engage the spring arms.

3. In combination, a container having a delivery nozzle provided with shoulders on opposite sides thereof, a cap for said nozzle, said cap being open sided, and hinge means connecting the cap to the container, said hinge means comprising spring arms embracing the cap and having tongue portions passing through the opening in the side of the cap to engage the shoulders of the nozzle, the ends of said spring arms being crossed, substantially as described.

4. A device according to claim 3 in which the cap is provided externally with grooved lugs engaged by said spring arms.

5. A container having a delivery nozzle provided with shoulders on opposite sides thereof, a cap for said nozzle, and a pair of arms movable towards and from each other and normally spring pressed towards each other, said cap being slotted and said arms having slot penetrating portions for engaging said shoulders.

In testimony whereof, I affix my signature.

CHESTER A. SPOTZ.
